(57) **CLAIM**

We claim the ornamental design for a front left side spoiler for a motorcycle, as shown.

DESCRIPTION

FIG. 1 is a left side elevation view of a front left side spoiler for a motorcycle showing our new design;

FIG. 2 is a right side elevation view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a right side perspective view, from the rear, thereof; and,

FIG. 8 is a left side perspective view, from the front, thereof.

1 Claim, 8 Drawing Sheets
